Primary Examiner — Cynthia Ramirez*Assistant Examiner* — Michael A Maharajh(74) *Attorney, Agent, or Firm* — Craft Chu PLLC;
Andrew W. Chu(57) **CLAIM**

The ornamental design for a refuse receptacle, as shown and described.

DESCRIPTION

FIG. 1 is an upper perspective view of the refuse receptacle showing my design;

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The solid surface lines in FIGS. 1-7 show curvature and continuous surfaces. The solid surface lines can be revised as contour lines. The broken lines shown in the figures are for the purpose of illustrating portions of the Refuse Receptacle, which form no part of the claimed design.
